UNITED STATES PATENT OFFICE.

JOHN C. McLAUGHLIN, OF NEW YORK, N. Y., ASSIGNOR, BY MESNE ASSIGNMENTS, TO UNDERWOOD TYPEWRITER COMPANY, OF NEW YORK, N. Y., A CORPORATION OF NEW JERSEY.

PAPER-EDGE GUIDE FOR TYPE-WRITING MACHINES.

SPECIFICATION forming part of Letters Patent No. 752,094, dated February 16, 1904.

Application filed February 5, 1903. Serial No. 141,964. (No model.)

To all whom it may concern:

Be it known that I, JOHN C. McLAUGHLIN, citizen of the United States, residing in the Borough of Manhattan, city, county, and State of New York, have invented certain new and useful Improvements in Paper-Edge Guides or Type-Writing Machines, of which the following is a specification.

My invention relates to type-writing machines, and has particular reference to means for guiding the edge of the paper at the point where the paper is inserted on the carriage.

The object of my invention is to provide a simple and readily-applied paper-edge guide which will be adjustable lengthwise of the platen, so as to fit paper sheets of various widths.

The invention will be fully described hereinafter and the features of novelty pointed out in the appended claims.

Reference is to be had to the accompanying drawings, in which—

Figure 1 is a partial plan of a type-writer carriage provided with my improved paper-edge guide. Fig. 2 is a sectional elevation on line 22 of Fig. 1, and Fig. 3 is an end view of the guide proper looking in the direction of the arrow in Fig. 2.

A indicates the platen, having a shaft A' and knob A², and B is part of the carriage-frame with the paper-shelf C at the rear of the platen. The paper-shelf is usually made with a round upper edge C' and generally has cut-out portions C² at the ends.

So far as above described the construction is or may be the usual one.

Upon the paper-shelf C, I mount adjustably the paper-edge guides D. These guides have angles D' projecting at right angles to their bodies D, and in the construction shown they are formed with curved members D², which are adapted to fit upon the curved upper end C' of the paper-shelf. The guides are thus adapted to be slid lengthwise on the upper edge C' of the shelf and may thus be adjusted to any point of the platen. The particular construction shown also enables the guides to swing on the upper edge of the paper-shelf,

so that the guides may be thrown against the shelf, as shown in Fig. 2, or moved toward the platen, if preferred. To securely hold the guides in position after adjustment and to prevent a marring of the paper-shelf by the guides, a lining E, of felt or other suitable material, is preferably provided within the curved portions D² of each guide.

It will be understood that the guides are set so that the distance between the flanges D' will correspond to the width of the paper, and then the sheet of paper is introduced between said flanges, which will thus cause the paper to be properly inserted under the platen. Whenever paper of a different width is substituted, the adjustment of the guides will be changed. The guides are so proportioned that they may be slipped off the paper-shelf at the cut-out portions C² without disturbing any part of the carriage.

Various modifications may be made without departing from the nature of my invention.

I claim as my invention and desire to secure by Letters Patent—

1. A paper-edge guide for type-writers and the like, comprising a curved member adapted to fit the curved free edge of a paper-shelf, a body member, and a flange extending at about a right angle to said body member and to the axis of the curved member.

2. In a type-writing machine or the like, a carriage having a platen, a paper-shelf with a rounded upper edge, and a paper-guide provided with a rounded portion arranged to fit the upper portion of the paper-shelf slidably and pivotally, the lower portion of said guide being freely movable toward and from the platen and terminating adjacent thereto.

3. In a type-writing machine or the like, a carriage having a platen, a paper-shelf, and a paper-guide the upper end of which is connected with said shelf pivotally and slidably, the lower portion of said guide being freely movable toward and from the platen and terminating adjacent thereto.

4. In a type-writing machine or the like, a carriage having a paper-shelf, and two paper-guides each provided with a body member par-

allel with said paper-shelf and arranged to cover a portion thereof, while leaving the portion of the shelf between said body members uncovered or exposed, the upper ends of said body members being connected with the paper-shelf pivotally and slidably, while the lower portions of said body members are freely movable toward and from said shelf, and each paper-guide being provided with a flange extending at about a right angle to the body member and to the pivot-axis thereof.

5. In a type-writing machine or the like, a carriage having a paper-shelf and two paper-guides extending downwardly in front of said

shelf from the upper edge thereof, said guide having a sliding engagement with the upper edge of the shelf and each of them comprising a body member parallel with the shelf and a flange extending at about a right angle to the body member and to the upper edge of the shelf.

In testimony whereof I have signed my name to this specification in the presence of two subscribing witnesses.

JOHN C. McLAUGHLIN.
